METHOD AND MEANS FOR PRODUCING METALLIC COATINGS ON ARTICLES SUCH AS
TYPE FORMS AND THE LIKE

Application filed December 22, 1924. Serial No. 757,454.

My invention relates to improvements in means and methods for producing a metallic coating on articles, particularly such as type forms, cuts, etc., which coating can later be stripped off and used in the production of duplicates of the article coated. In other words, my invention relates to novel means and methods of accomplishing the same result as is now done by the well known electrotype process of the reproduction and duplication of type forms etc., but in a much quicker, cheaper and more satisfactory manner.

My invention includes the production of a suitable metal in molten form and delivered in a relatively small stream, and the atomizing, driving and compacting of this molten metal upon the article to be coated. While many inventors have worked along these lines, so far as I am aware, none of them has succeeded in producing a method which has merit sufficient to cause its adoption in lieu of the well known, though not wholly satisfactory electrotype methods.

One feature of importance inherent in my novel method is that the article can be coated in a very short time and as soon as this is done the coating can immediately be stripped off and made use of as a matrix in the production of copies of the original.

By means of my novel method the time required to produce a copy of the original is reduced to but a few minutes. The electrotype method requires a certain time to deposit the metal by electricity and the papier-mâché method requires time for drying the matrix, and further by this latter method the reproduction is not good enough for many uses.

I provide simple mechanical means for atomizing the molten metal and driving it upon the article, and I preferably, though not necessarily use electrical means to produce the molten metal. The preferred form of my mechanism includes means for feeding two wires to a point where they are fused by an electric current, in combination with an electromagnetic circuit breaker by which an electric arc is produced and by which the wires are fused.

My invention will be more readily understood by reference to the accompanying drawings in which I have illustrated my novel means for practicing my improved method, and in which:

Figure 1, is a top plan view partly diagrammatic, of my improved apparatus;

Figure 2, is a side elevation of the apparatus shown in Figure 1; and

Figure 3, is a side elevation of a slightly modified form of apparatus.

In the apparatus illustrated in Figures 1 and 2, 1 illustrates a suitable frame upon which the several parts of the apparatus are mounted. I provide supplies of two fusible wires 2 and 3, preferably by providing two spools of the wire 4 and 5, respectively, rotatably mounted on one end of the frame 1 from which the wire can be unrolled as needed. At the opposite end of the frame I provide an impeller 6 in the form of a paddle wheel, having radial arms 7. The paddle wheel is preferably mounted with its axis vertical. It is secured on a vertical shaft 8. Any suitable means may be provided to rotate the impeller, such as horizontal shaft 9, carrying a belt pulley 10 and geared to the shaft 8 by the bevel wheels 11. Preferably I incline the outer ends 7' of the impeller arms 7, to their direction of motion, so that as they strike the molten metal there will be a tendency to deflect and spread the molten metal over a relatively large area. This spreading of the metal tends to produce a more evenly applied coating of the metal on the article being coated.

I provide means for feeding the two wires 2 and 3 in such a way as to be brought into contact with each other at a point in proximity to the sweep of the ends of the arms 7 of the impeller 6 as the same is rotated. The wire feeding and guiding means consists of pairs of upper and lower feed rolls 12 and 13, respectively, between which the two wires are guided by suitable guides 14 and 15, arranged at the two sides of the pairs of rolls. The upper and lower rolls are mounted on parallel horizontal shafts 16 and 17, respectively, and the shafts can be arranged to bind and feed the wires by any suitable

means, such as movably mounting the lower shaft 17 in relation to the upper shaft and providing springs 18 for yieldingly holding the shaft 17 pressed toward the shaft 16.

5 Preferably I make the springs 18 adjustable as to pressure by adjustable screws 19.

I have indicated a simple means for rotating the upper shaft 16 for feeding the wires, this consists of a ratchet wheel 20 secured 10 on one end of the shaft and engaged by one end of a push rod 21, the opposite end of which is mounted upon an eccentric pin 22 projecting from a hub 23 secured to the adjacent end of the shaft 9. The arrangement is 15 such that for each revolution of the shaft 9 the ratchet wheel is rotated the space of one tooth. It is obvious that other simple feed means could be provided.

For guiding the wires to meet at a point 20 in proximity to the ends of the impeller arms, I provide two guide tubes 24 and 25 for the wires 2 and 3, respectively, which are inclined to each other and their delivery ends 26 and 27, respectively, are arranged close 25 together and adjacent to the periphery of the impeller. The guide tubes are made of insulation material so that I can make use of an electric current to fuse the wires. Preferably I make the guide tubes 24 and 25 30 relatively slightly movable to permit the separation of the ends of the wires for the production of an electric arc for the purpose of fusing the wires.

I have shown the guide tube 25 as fixed 35 and the guide tube 24 as hingedly mounted at its rear end at 28, so that its forward or delivery end 26 can be swung from and toward the delivery end 27 of the tube 25. I provide means, such as the spring 29, for yieldingly holding the delivery ends 26 and 27 of the guide tubes close together so as normally to retain the free ends of the wires 2 and 3 in contact with each other.

For the purpose of drawing the ends of 40 the guide tubes 24 and 25 apart for separating the free ends of the wires, I provide an electro-magnet indicated at 30 which, when energized is adapted to attract a soft iron armature 31 secured to the movable guide tube 24 and swing this tube on its pivot 28 away from the other guide tube. Between the wire guides 15 and the adjacent ends of the guide tubes, I provide spring contacts 32 and 33 for the wires 2 and 3, respectively, 45 through which means I connect the two wires with a suitable source of electricity 34. It is understood, of course, that the construction of the apparatus is such that the wires 2 and 3 are insulated from each other so that when 50 their free ends are brought into contact with each other an electric circuit, including the ends of the wires, can be closed. One circuit wire leads to the electro-magnet and the other to one of the fusible wires, and the 55 other fusible wire is connected to the elec-

tro-magnet winding. By this means when the ends of the fusible wires are in contact, and the electric circuit is closed, the magnet is energized and serves to separate the ends of the wires. The breaking of the circuit by 70 the separation of the wires produces an electric arc which serves to fuse the ends of the wires. At the same time the impeller is rotating at a relatively high speed and the free ends of the impeller arms are arranged 75 to strike the metal as it is fused and knock it into a fine spray of molten metal driving it downwardly and tending to spread it over a considerable area.

The aim and object of my invention is to 80 provide a simple and reliable means for producing a spray of molten metal, particularly for the purpose of producing a thin substantially even coat of metal upon such an article as a type or printing form or cut 85 which it is desired to reproduce. As illustrative, merely of the use and purpose of my invention, I have shown such an article to be coated at 35. It is obvious that suitable means could be provided for moving the article 35 about under the spray produced by my apparatus, so that the whole exposed surface of the article could be coated as desired.

Instead of the production of the molten 90 metal by means of an electric current, as illustrated in Figures 1 and 2, I sometimes prefer to produce the molten metal in a simpler manner by heat, and in Figure 3 I have indicated a suitable apparatus for this 95 purpose. In this instance I provide a pot 40 to contain the metal and a suitable source of heat, such as a gas burner 41 beneath the pot for melting the metal. Leading out from the pot is a delivery spout or tube 42, and beneath the delivery tube I arrange a gas 100 burner 43 to keep the metal hot as it flows through the tube. Adjacent to the end of the tube I arrange an impeller 44, preferably in this instance, on a horizontal shaft 105 and rotatable by any suitable means. The impeller is arranged so that the ends of its arms sweep past the delivery end of the feed tube 42 and strike the metal falling out of the tube and are adapted to knock the molten 110 metal into extremely fine particles and drive them with considerable force upon the article to be coated, such as that shown at 45. For the purpose of regulating the flow 115 of metal a screw 46 can be arranged at the delivery end of the tube 42 adapted to be entered into the tube more or less as desired.

As many modifications of my invention 120 will readily suggest themselves to one skilled in the art, I do not limit or confine my invention to the specific details of construction herein shown and described.

I claim:

1. The herein described method of coating 125 articles with metal which includes the pro-

- vision of a substantially constant feed of a relatively small stream of metal in a molten state, and mechanically knocking this stream of metal into infinitesimal particles and the impelling of these particles, still in molten condition, upon the article to be coated. 5
2. In a mechanism of the kind described, means for producing a substantially constant stream of molten metal, in combination with means for delivering a quick succession of mechanically applied blows on the stream, whereby the stream is broken up into substantially infinitesimal particles and driven against a surface to be coated with the metal. 10
3. In a mechanism of the kind and for the purpose described, a means for guiding two fusible wires to a point of contact, a source of electric current for fusing the wires, the wires forming part of the electric circuit, electro-magnet means operable by the same electric current for separating the two wires at their point of contact, whereby the circuit is broken at said point and the wires 15 fused, means for striking the metal as fused and breaking it into substantially infinitesimal particles and impelling the particles against a surface to be coated, means for operating the striker and means cooperating therewith for feeding the wires to the point of contact. 20
4. In a mechanism of the kind described, electrical means for feeding two fusible wires into contact in a fusing zone, electrical means for fusing the wires in said zone, and a rotatable member provided with arms, each provided with a palm-like surface at its ends adapted to strike the stream to break it into substantially infinitesimal particles 25 and to drive the particles in the form of a widely divergent spray-like stream against a surface to be coated. 30
5. In a mechanism for the purpose described, two guide tubes of insulation material adapted to guide two fusible wires, the guides adapted to direct the wires so that their free ends contact at a melting zone, a source of supply of electric current, the wires adapted to form part of the circuit, the electric current sufficient to fuse the wires as 35 they are separated, means for vibrating one of the tubes to alternately separate the wires and bring them together again, a rotatable member having arms provided on their ends with surfaces adapted to pass through the metal melting zone and impel the metal 40 against a surface to be coated. 55
6. In a mechanism of the kind described, means for producing a substantially constant stream of molten metal, in combination with rapidly rotating means for delivering a rapid succession of blows on the stream, whereby the stream is broken up into substantially infinitesimal particles and driven 45 against a surface to be coated with the metal. 65
7. The method of coating articles with metal which includes the provision of a substantially constant feed of a relatively small stream of the metal in a molten state, dividing the stream into relatively small sections and independently driving the sections against the article to be coated, the article being located at such a distance that the metal is still in a molten state when it strikes the article and a sheet of the metal is produced on the surface being coated. 70
8. The method of coating a printing form or the like with metal which method consists in providing a substantially constant feed of a relatively small stream of the metal in a molten state, subjecting the stream to a rapid succession of separate and distinct blows, thereby dividing the stream into a succession of relatively small distinct sections and driving the sections independently against the form to be covered, the form being located at such a distance that the metal strikes the form in a sufficiently molten state to form a sheet covering the form. 75
9. The herein described method of covering printing forms and such like articles with a coating of metal, which includes the provision of a substantially constant stream of the metal in a molten condition and the application of a rapid succession of blows upon the stream, and thereby breaking up the stream into infinitesimal particles and driving them with relatively great violence against the article to be coated, the article being located at such a distance that the particles are still in molten condition when they strike the article. 80
10. In a mechanism of the kind described, means for producing a substantially constant stream of molten metal in combination with an impeller in the form of a rapidly rotatable member, having arms arranged at an angle other than a right angle to the plane of rotation and adapted to strike the stream and break it into infinitesimal particles and drive them against a surface to be coated. 105
